(57) **CLAIM**

The ornamental design for a mobile x-ray unit with integrated x-ray shield, as shown and described.

DESCRIPTION

FIG. 1 is a rear perspective view of a mobile x-ray unit with integrated x-ray shield;

FIG. 2. is a front perspective view thereof;

FIG. 3 is a front elevational view thereof;

FIG. 4 is a rear elevational view thereof;

FIG. 5 is a right side elevational view thereof;

FIG. 6 is a left side elevational view thereof;

FIG. 7 is a top view thereof; and,

FIG. 8 is a bottom view thereof.

The broken lines in the drawing views are included for the purpose of illustrating portions of the mobile x-ray unit with integrated x-ray shield that form no part of the claimed design.
